UNITED STATES PATENT OFFICE.

ADOLPH C. RECKER, OF OAKVILLE, CONNECTICUT, ASSIGNOR TO THE CHASE COMPANIES INC., OF WATERBURY, CONNECTICUT, A CORPORATION.

ELECTRICAL ATTACHMENT PLUG.

1,425,694.

Specification of Letters Patent. Patented Aug. 15, 1922.

Application filed August 26, 1919. Serial No. 319,913.

To all whom it may concern:

Be it known that I, ADOLPH C. RECKER, a citizen of the United States, residing at Oakville, in the county of Litchfield and State of Connecticut, have invented a new and useful Improvement in Electrical Attachment Plugs; and I do hereby declare the following, when taken in connection with the accompanying drawings and the characters of reference marked thereon, to be a full, clear, and exact description of the same, and which said drawings constitute part of this application, and represent in—

Fig. 1, A view of side elevation of an electrical attachment-plug, constructed in accordance with my invention.

Fig. 2, An edge view thereof partly in longitudinal section.

Fig. 3, A plan view thereof with one of the body-members removed.

Fig. 4, A view thereof in transverse section through the lower of the two bolts employed to secure the two body-members together.

Fig. 5, A detached edge view of one of the pairs of jaws.

Fig. 6, An enlarged plan view of one of the jaws shown as folded and shaped, ready for use.

Fig. 7, A plan view of the blank from which the complementary jaw is folded.

Fig. 8, An enlarged view in transverse section of one pair of jaws at rest or un-plugged.

Fig. 9, A corresponding view showing the introduction of a round contact-finger between the jaws.

Fig. 10, A corresponding view showing the introduction of a flat contact-finger between the jaws.

My invention relates to an improvement in electrical attachment-plugs (so called in the trade) designed to be mounted upon the ends of flexible wires or leads, and to be plugged into socket-fixtures mounted in heating and lighting utensils or kindred appliances containing contact-fingers which when the attachment-plug is applied to the fixtures, enter between the yielding jaws in the plug, the object of my invention being to produce a compact, convenient and efficient electrical attachment-plug of the type described.

With these ends in view, my invention consists in an electrical attachment-plug

having the side edges of its pairs of jaws rolled inward to form yielding contact-leaves.

My invention further consists in an electrical attachment-plug having certain details of construction as will be hereinafter described and pointed out in the claims.

In carrying out my invention, I employ a plug-body consisting of complementary oblong chambered body-members 2 and 3 made of insulating material and having square inner and rounded outer ends, the latter being transversely bulged as at 4 to produce, when the two members are united, what is known as a "pistol grip." Located within each chambered body-member, is a central longitudinal partition 5 extended to its square inner end, but stopping short of its rounded outer end and flush with its edges. Bolts 6 passing through perforations 7 in the said webs, secure the two body-members together to form the plug-body which, as thus constructed, contains two parallel jaw-chambers 8 merging at their outer ends into a knot-chamber 9 which occupies the "pistol grip" end of the plug-body which has a central opening 10 leading out of the said knot-chamber, in which the leads 11 and 12 are knotted as at 13, whereby the strain is removed from the terminal or binding-screws 14 in case the outer ends of the wires are pulled upon to remove the plug from its socket (not shown) as is oftentimes carelessly done. The said knot-chamber 9 is a relatively large, unobstructed, open space located within the outer end of the plug-body, extending transversely to the axis thereof, and co-incident with the transversely arranged bulges 4 upon the outer faces of the outer ends of the body-members. The said knot-chamber is ample in its capacity to receive the knots prescribed by the underwriters.

My improved jaws which are located within the respective jaw-chambers 8, are designed with particular reference to adapting them to receive and make efficient contact, either with flat sheet-metal or round contact-fingers, in various makes of sockets varying somewhat as to form and size, depending upon the character of the appliance in which the sockets are mounted. As shown, the respective jaws 15 and 15^a of each pair, are alike, except that the jaw 15 is formed with a longer shank 16 than the 110

shank 17 of the jaw 15, the said shank 16 being folded over the shank 17, as shown in Fig. 5, and the said shanks being perforated for the reception of the binding-screws 14 employed to connect the leads or wires 11 and 12 with the jaws which, if preferred, might be made from one piece of sheet-metal. The side edges of the jaws are rolled inward so as to form resilient contact-leaves 19, the edges of which are separated from the flat inner faces of the jaws by accommodation-spaces 20, as clearly as shown in Fig. 8. The outer ends of the jaws are flared as at 21 sufficiently to facilitate the entrance of the contact-fingers between the jaws, when the plug-attachment is plugged into the socket.

Fig. 9 of the drawings shows the introduction of a round terminal or contact-finger 22 between the jaws which are slightly spread apart thereby. The resilient leaves of the jaws are also shown as sprung into the accommodation-spaces 20 aforesaid. Fig. 9, therefore, illustrates the accommodation of the jaws to a round contact-finger slightly over size. It will be understood, of course, that the jaws are set to accommodate the smallest round contact-fingers likely to be met with, and yet spring far enough to take

in the largest. Fig. 10 shows the introduction of a flat contact-finger 23 between the jaws, the rounded edges of which rest upon the finger near the edges thereof.

I claim:—

An electrical attachment-plug having a plug-body, and a pair of jaws located therein, each jaw having an integral perforated shank of which the shank of one jaw is longer than the shank of the other jaw and folded over the same to unite the two jaws and each jaw having its side-edges rolled inward to form contact leaves and the said jaws spreading apart for the accommodation between them of flat contact-fingers and also for the accommodation of round contact-finger, and the said folded leaves yielding under the action of round contact-fingers after the jaws have reached the limit of their spreading apart by contact with the interior walls of the said plug-body.

In testimony whereof, I have signed this specification in the presence of two subscribing witnesses.

ADOLPH C. RECKER.
